(57) **CLAIM**

The ornamental design for a patient control, as shown and described herein.

DESCRIPTION

FIG. 1 is a front, top, right perspective view of a patient control;

FIG. 2 is a top plan view thereof;

FIG. 3 is a bottom plan view thereof;

FIG. 4 is a front view thereof;

FIG. 5 is a rear view thereof;

FIG. 6 is a right side view thereof; and,

FIG. 7 is a left side view thereof.

The broken lines in the Figures are included for the purpose of illustrating portions of the patient control that form no part of the claimed design.
